US0D1062525S

(12) **United States Design Patent** (10) **Patent No.:** **US D1,062,525 S**
(45) **Date of Patent:** **** Feb. 18, 2025**

(54) **SNAP BUTTON**

(71) Applicant: **YKK Corporation**, Tokyo (JP)

(72) Inventors: **Naoki Kasuya**, Seoul (KR); **Yong Chul Lee**, Seoul (KR); **Kyong Ah Kim**, Seoul (KR); **Jun Won Lee**, Seoul (KR)

(73) Assignee: **YKK CORPORATION** (JP)

(**) Term: **15 Years**

(21) Appl. No.: **29/843,589**

(22) Filed: **Jun. 22, 2022**

(30) **Foreign Application Priority Data**

Dec. 24, 2021 (KR) 30-2021-0062316

(51) **LOC (15) Cl.** **02-07**

(52) **U.S. Cl.**

USPC **D11/222**; D11/224; D11/228

(58) **Field of Classification Search**

USPC D11/200, 220, 222, 223, 224, 226, 238, D11/239, 240, 228; D8/388, 397;

D2/609, 639, 853, 976; D3/322

CPC ... A44B 17/00; A44B 17/007; A44B 17/0005;

A44B 17/0029; A44B 1/34

(57) **CLAIM**

The ornamental design for a snap button as shown and described.

DESCRIPTION

FIG. 1 is a front perspective view of a snap button showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

1 Claim, 8 Drawing Sheets
